UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,335, dated October 1, 1889.

Application filed August 19, 1889. Serial No. 321,177. Term of patent 3½ years.

To all whom it may concern:

Be it known that I, ADOLPH PETZOLD, a resident of Philadelphia, Pennsylvania, and a citizen of the United States, have invented 5 a new and original Design for Rugs, of which the following is a description, reference being had to the accompanying photographic illustration, making part hereof.

The leading features of my design consist 10 of an outer rectangular or oblong border with scalloped edges outwardly, ornamented with figuring at intervals, a middle panel with a center piece of interlocked scroll-work and ornamental scrolls in the corners.

15 A is the outer oblong border; B B, the or-

namental fanciful figures thereon; C, the middle panel; D, the center piece of scroll-work; E E, the ornamental scrolls in the corners of panel C.

What I claim is—

20 The design for a rug, consisting of the oblong border A, with ornamental figures B B thereon, middle panel C, center piece D of ornamental scroll-work, and corner scrolls E E, all substantially as shown.

ADOLPH PETZOLD.
